CLAIM

The ornamental design for a retracting headlight assembly, as shown and described.

DESCRIPTION

FIG. 1 is a front perspective view of the retracting headlight assembly showing my new design.

FIG. 2 is a front elevation view thereof.

FIG. 3 is a rear elevation view thereof.

FIG. 4 is a left side view thereof.

FIG. 5 is a right side view thereof.

FIG. 6 is a top plan view thereof.

FIG. 7 is a bottom plan view thereof.

FIG. 8 is a front perspective view showing the headlight assembly in use, in an open position; and,

FIG. 9 is a front perspective view showing the headlight assembly in use, in a closed position.

The broken lines shown in the drawings illustrate portions of the retracting headlight assembly that form no part of the claimed design.

The broken lines in FIG. 8 and FIG. 9 showing the retracting headlight assembly in use illustrate environment and forms no part of the claim.

1 Claim, 6 Drawing Sheets
